US0D1014736S

(12) **United States Design Patent** (10) **Patent No.:** **US D1,014,736 S**
(45) **Date of Patent:** **** Feb. 13, 2024**

(54) **PIPETTE SYRINGE**

(71) Applicant: **Mettler-Toledo Rainin, LLC**, Oakland, CA (US)

(72) Inventors: **Richard Hill**, Berkeley, CA (US); **Michael McNaul**, Sunnyvale, CA (US); **Jamie McPherson**, Cambridge (GB); **Stephen Grimwade**, Upwood Huntingdon (GB)

(73) Assignee: **Mettler-Toledo Rainin, LLC**, Oakland, CA (US)

(**) Term: **15 Years**

(21) Appl. No.: **29/884,874**

(22) Filed: **Feb. 16, 2023**

CLAIM

The ornamental design for a pipette syringe, as shown and described.

DESCRIPTION

FIG. 1 is a top-front perspective view of a pipette syringe; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a bottom-rear perspective view thereof.

The broken lines in the drawings illustrate portions of the pipette syringe and form no part of the claimed design.

1 Claim, 5 Drawing Sheets
